Filed July 16, 1959, Ser. No. 827,532

4 Claims. (Cl. 313—82)

This invention relates to electronic apparatus and more particularly to electron emitters for cathode ray tubes.

It is the basic object of the present invention to provide an improved and new form of electron emitting device particularly useful in the so-called "electron gun" of cathode ray tubes of the television type.

More specifically it is an important object of this invention to provide an arrangement in an electron emitter providing for a simpler assembly while holding close tolerances between the actual emitting surface and the apertured area of the number one grid.

An important object of the invention resides in the construction of the electron emitter assembly whereby leakage across the insulation which supports the cathode sleeve from the grid cylinder is materially reduced by the provision of shadowed areas thereon.

Another important object of the invention comprises the mounting of the cathode cylinder in its ceramic support disc so that a large percentage of its length extends above the disc and only small percentages are incased in the disc or extend below it, whereby heat loss is kept to a minimum, and evaporation and sublimation, which cause current leakage, cannot occur in critical areas.

Still other objects and features of the invention include, simplified assembly procedure, close tolerances where critical, low mass and cost of components and improved operating efficiency.

Further features and objects of the invention will be more apparent to those skilled in the art upon a review of the following specification and accompanying drawing wherein is disclosed a single exemplary embodiment of the invention, it being understood that such variations and modifications may be made therein as fall within the scope of the appended claims without departing from the spirit of the invention.

In said drawing:

FIG. 1 is a side elevation of an electron gun construction in accordance with the present invention, shown in position in the neck of a television type of cathode ray tube, the neck being shown broken away for clearer illustration; and

FIG. 2 is a longitudinal, central section through the grid cylinder, grid tube insulator, cathode tube and cathode assembly illustrating the important features of the invention on an enlarged scale.

The television set version of a cathode ray tube, in the vernacular a "picture tube," includes an elongated neck housing one or more so-called "electron guns" each adapted to direct a concentrated beam or ray of electrons toward the fluorescent viewing screen at the front of the tube, to produce the desired picture effect after proper vertical and horizontal deflection, as well understood.

Extreme care in the design and construction of the electron gun is called for if long life, satisfactory performance and high efficiency are required. Fine tolerances for the assembly of certain of the parts are required and unusual shaping and relationship of some of the components is essential to assure the fulfilment of the rigid requirements set forth above and others as will later appear. The present invention is concerned with such construction, arrangement and assembly of these parts to insure more efficient electron emission, its control as to direction and beam concentration, and insurance against leakage across the cathode supporting insulator.

2

Reference should now be had to FIGURE 1 for a general disclosure of the neck and connection base section of a "picture tube" fitted with an electron gun, the number one grid and cathode assembly of which is constructed in accordance with the present invention. In this figure, 10 represents the glass wall of the tube neck fitted with the usual base 11 mounting the conventional arrangement of contact pins and central orienting plug, all as is generally known.

10 Within the neck and supported from conductor and pillar wires arranged in the tube "press" is the assembly 12 generally referred to as an "electron gun," including, among other things, a cathode, cathode heater, the number one grid, one or more additional grids and one or more anodes arranged generally in the order named and longitudinally of the tube neck starting from the base. The several components are mechanically connected together by suitable mountings and attachments to longitudinally directed ceramic rods 13, while the top disc 14 is fitted with radially disposed spring fingers 15 engaging the walls of the neck for stabilizing and centering the gun assembly therein. This is more or less conventional construction and may be varied to suit particular situations or the desires of the individual tube manufacturer.

25 The cathode, the number one grid and the insulator mounting the former from the latter compose the sub-assembly forming the subject matter of the present invention and this is shown in greater detail and on a larger scale in FIGURE 2 and designated 16 in both figures.

30 The main component of the sub-assembly 16 is the large diameter grid cylinder 18 drawn from appropriate metal of relatively thin gauge and having the straight cylindrical wall extending upwardly from the open bottom 19, normal to the axis of the cylinder, to the curved junction 20 between the sidewall and the flat annulus 21 partially closing the upper end of the grid cylinder.

35 The inner edge of the annulus meets at 22 and is integral with the cylindrical wall 23 of the grid tube having the integral flat top closure 24, centrally perforated as at 40 25 by a circular aperture permitting egress of the beam or ray of electrons generated by the heated cathode for impingement on the fluorescent viewing screen (not shown) after two-way deflection.

The annulus 21 is deeply channeled inwardly as at 27 45 providing a ring or bead 28 protruding downwardly from its under surface whereby to separate the flat upper face 30 of the ceramic or insulating disc 31 from the main area of the annulus. This disc is cylindrical and its sidewall 32 is such as to fit with reasonable closeness within

50 the wall 18 of the grid cylinder. The ceramic disc or insulator is held in position against bead 28 by having the perimeter of its flat lower face 33 engaged by the turned flange 34 formed integral with the short skirt 37 welded to the wall of cylinder 18 while being held tightly against the under face of the ceramic disc. Obviously other securing means such as a bead rolled into the wall of cylinder 18, or prongs or tabs bent inwardly therefrom to engage the under face of the disc would be optional.

60 The ceramic insulating disc is unique in construction as will be seen from FIGURE 2 for it is provided with a deep, large diameter well 40 extending therein from the upper surface and having a flat bottom 41 spaced reasonably close to the under surface of the disc. The top face 65 30 of the disc is spaced below the annulus 21 by virtue of bead 28, but the inner cylindrical wall 42 of the well 40 extends up and partially into the grid tube 23 where it is defined by the relatively thin, annular wall 43 extending upwardly from the surface 30 and formed integral with disc 31. The outer cylindrical surface 44 of wall 43 is shown to be spaced radially from the inner wall of

the grid tube 23 by the clearance 45, only large enough to prevent contact and possible electrical leakage.

The cathode tube, which is adapted to receive and house the heater comprises an open end metal cylinder 47 passing through a cylindrical aperture 48 in the relatively thin wall between the bottom 41 of the well and the bottom face of the ceramic disc. The wall of aperture 48 has a close fit to the outer diameter of the cylinder. The well 40 may be considered as a counter-bore for aperture or bore 48.

The cathode tube is assembled in the ceramic prior to the latter being secured in the grid cylinder 18 and the procedure is preferably as follows. A bead such as that illustrated at 49 is rolled on the cylinder to limit its extension through aperture 48 when it is inserted through the well. An alternative means would be to weld a flange or rim in place of bead 49. When the cylinder 47 is properly positioned with this bead against the bottom 41 of the well, the second bead 50 is rolled against the underface 33 of the disc to lock the cathode tube firmly in position and, then, preferably the lower end of the tube is slightly flared as at 51 to facilitate the insertion of the heater assembly.

The arrangement just described is such that approximately seventy percent of the cathode cylinder extends above the well bottom 41 and approximately ten percent protrudes beneath the lower face of the ceramic disc whereby very little heat loss results and no evaporation or sublimation is effected by the lower protruding portion which might cause leakage between the cathode and the grid. However, enough of the cylinder protrudes beneath the disc to allow welding the cathode tab 54 there-to as shown. Heat loss is particularly critical in cases where the cathode cylinder is of small diameter and low current heaters are used. Any substantial heat loss might well shorten the life of the cathode ray tube by reducing emission as efficiency falls.

The cathode cylinder 47 may be drawn with an integral closed head if desired, but it is preferably to close the upper end by means of a telescoped metal cap 56 as shown. This has several advantages, among which may be mentioned the selection of a superior metal which can be used in lesser quantity, a choice of thickness and a better flattening of the actual closure head 57 and, finally, the possibility of more accurately adjusting the spacing between the front surface 30 of the ceramic disc and the face of the closure head 57 prior to welding it into the position shown. This permits a very accurate control of the spacing of head 57 from head 24 which is essential for proper beam control. As shown, the head 57 is covered with coating 59 of an emissive material, the composition of which is open to choice and many are well-known.

Although the major emission takes place from the coating 59, the metal of the tube 47 and of the cap 56 is heated, at least during processing prior to and during evacuation, to such a temperature that there is a certain amount of evaporation and/or emission from their outer surfaces which might so coat the upper face 30 and the walls of the well 40 as to produce a substantial degree of current leakage between the cathode cylinder and the number one grid cylinder 18 where its bead 23 engages the face 30.

This type of loss is substantially eliminated by the present construction, first by forming the deep well 40, which increases the path between the two metal surfaces over that which would exist if the well were not in existence, and, secondly, the collar or protective wall 43 extends upwardly to intercept any evaporation or emission from any area of the cathode cylinder and completely shadow out or protect the top surface 30 of the ceramic. The outer surface of wall 43 is also protected against coating. The clearance 45 between the wall 43 and the inner surface of grid tube 23 is so adjusted in respect to the height of the wall that no straight path exists from the highest point on the cathode cylinder or

its cap to any of the area of the disc surface 30, whereby insulation resistance remains high.

It will be appreciated that adjusting of the spacing of the head 57 above the surface 30 of the ceramic disc 5 may be effected by the use of apparatus not substantially different in form and operation from that illustrated in FIGURE 5 of the patent to L. E. Griffiths, 2,758,236 granted August 7, 1956, and checking of this critical distance may be effected on a dial gauge arrangement as illustrated in FIGURE 6 of that patent.

The assembled cathode cylinder and ceramic disc may be used in a more conventional number one grid cylinder, which is of uniform diameter throughout its height, by substituting for the annulus 21 and the positioning bead 27, the proper length tube or cylinder of metal flanged or footed if desired to rest on the surface 30 and having its other end engaging the under surface of the full diameter closure of the grid cylinder. Here the accuracy called for is in the length of this spacer which not only serves for dimensional control but shields the area of the disc outside of its perimeter from emissive material. In either assembly there is always at least a shadowed area 30 just outside of the wall 43 due to the substantially lesser diameter of the cathode tube than that of the wall 43.

I claim:

1. A sub-assembly for use in the first grid cylinder of a cathode ray tube comprising, in combination, a thick disc of insulation material sized to closely fit within the lower portion of said cylinder and having substantially flat top and bottom faces, a central bore through said disc, a counterbore forming a well opening through the top face and having a depth more than two-thirds the thickness of the disc, as integral wall above the top face having its inner surface coextensive with the well wall, a cathode tube projecting through and secured in said bore and having of the order of 10 percent only of its length depending below said bottom face and of the order of 70 percent projecting above the well bottom, and at least 25% extending above the top of said wall.

2. A sub-assembly for use in a stepped diameter first grid cylinder of a cathode ray tube having a flat annulus connecting the large and small diameter cylinders, in combination, spacer means on said annulus and remote from both diameters thereof projecting a predetermined distance into the large diameter cylinder, a single, thick disc of insulating material sized to fit in said large cylinder and having a flat upper face area engaging said spacer means, means on said cylinder maintaining the disc face against said spacer, a cathode tube extending axially through and secured in only said disc, a cap telescoped on the upper end of said tube adjusted so that its flat top is spaced a predetermined and substantial distance from said disc upper face, means incorporated within said disc for extending the leakage path thereover between the cathode tube and said spacer means, and upwardly extending means integral with said disc shadowing an annular area of said disc upper face against contamination from said cathode tube.

3. For use in an electron gun for cathode ray tubes, 60 in combination, a number one grid cylinder having tandem arranged co-axial, large and small diameter portions, one about twice the diameter of the other, and an annular connecting portion, a perforated grid disc closing the remote end of the small diameter portion, integral spacing means on said annular portion projecting toward the remote end of the larger diameter portion, a single, thick insulating disc sized to fit into said large diameter portion and having a flat top engaged by said spacing means for positioning said disc a fixed distance 65 from the flat underface of said annular portion, said disc having a central aperture of less diameter than said small diameter portion of the grid cylinder and an open topped well co-axial with said central aperture, a cathode tube fixed in said aperture and having a closed 70 end positioned close to said perforated grid disc, said 75

cathode tube projecting above the well bottom about 70% of its length to radiate most of its heat above the insulation disc, a radially thin annular barrier wall extending upwardly from said insulating disc, spaced from the cathode tube a distance substantially half of the tube diameter and entering said small diameter portion of said grid cylinder and spaced but slightly from the inner wall thereof, said cathode cylinder extending substantially above the top of said barrier wall and the wall of said well and the inner wall of said barrier being co-extensive.

4. For use in an electron gun for cathode ray tubes, in combination, a number one grid cylinder having tandem arranged co-axial, large and small diameter portions, one about twice the diameter of the other, and an annular connection portion, a perforated grid disc closing the remote end of the small diameter portion, integral spacing means on said annular portion projecting toward the remote end of the large diameter portion, a single thick insulating disc sized to fit into said large diameter portion and having a flat top engaged by said spacing means for positioning said disc a fixed distance from the flat underface of said annular portion, said disc having a central aperture of less diameter than said small diameter portion of the grid cylinder and an open topped well co-axial with said central aperture, a cathode tube

fixed in said aperture and having a closed end positioned close to said perforated grid disc, radially thin annular barrier wall extending upwardly from said insulating disc, spaced from the cathode tube a distance substantially half of the tube diameter and entering said small diameter portion of said grid cylinder and spaced but slightly from the inner wall thereof, said cathode cylinder extending substantially above the top of said barrier wall, the wall of said well and the inner wall of said barrier being co-extensive, said closed end on said cathode tube comprising a one-piece cap having a flat top and an integral cylindrical skirt telescoped over the cathode tube a distance adjusted to provide a predetermined spacing from the ceramic disc top to the cap top whereby the cap top has a predetermined clearance from the underface of the grid disc for beam control.
